UNITED STATES PATENT OFFICE

ALBERT W. MORSE, OF LONG ISLAND CITY, NEW YORK

RADIANT-HEAT OVEN

Application filed August 5, 1926. Serial No. 127,350.

This invention relates to radiant heat ovens, and has for its particular object to provide an oven which is used for the heat treatment of articles by subjecting them to radiant heat caused by an oil burning device which, however, due to its novel application, has none of the disadvantages associated at times with oil burning appliances employed heretofore for such purposes.

10 It is the principal object of the invention to duplicate the performance of a heat treating oven which is operated by electrical heating elements with units which are oil fired, whereby the excellent working characteristics 15 of electrical elements are combined with the low operating cost of oil fuel.

With this end in view, I provide within an oven of this kind, oil fired tubes which have walls adapted to radiate heat within the work 20 chamber of the oven, these tubes being in spaced relation to the walls of the work chamber, so that the greatest amount of heat units from the tubes will be utilized within the chamber causing a uniform and highly 25 efficient distribution of heat.

The radiation from oil fired tubes of this character is as easily controlled as that from electrical heating elements, while their operating cost is much less owing to the lower 30 cost of the oil fuel. No products of combustion are brought in contact with the work, nor can excess air which is liable to chill and injure the work be drawn into the work 35 chamber by the draft or the velocity of burner jets or on account of faulty regulation of oil and air volumes incidental with the prevailing type of oil fired ovens.

Other objects of the invention will become apparent in the following specification and 40 the accompanying drawings illustrative of preferred embodiments of the same, and in which

Fig. 1 is a front elevational view of an oven embodying oil fired radiant units;

45 Fig. 2 is an enlarged vertical cross sectional view through the oven and one of the units along the plane of line 2-2 in Fig. 1;

Fig. 3 is a horizontal sectional view through the oven showing a modified arrangement of 50 radiant units;

Fig. 4 is a similar fragmentary sectional view through an oven of extra length, several units being connected together in series;

Figs. 5 to 10 illustrate diagrammatically vertical sectional views through various types 55 of ovens showing preferred applications of radiant units thereto;

Fig. 11 shows different cross sectional views of the tube forming part of the radiant unit; and

Figs. 12 and 13 longitudinal sectional views of modified shapes of the same.

Like characters of reference denote similar parts throughout the several views and the following specification.

20 is an oven, mounted upon a base 21, having a door 22. A work chamber 23 forming the inner part of the oven is lined with refractory material 24 which is surrounded by suitable insulating material 25 and an outer 70 metal housing 26 of the oven.

Reference to Figs. 1 and 2 shows to the front of oven 20 suitably attached a preferably rectangular flange 27. The center of the flange is threaded at 28 to engage one end of a so-called "radiant" tube 29. The other end of the tube 29 projects outwardly of the oven through its rear and is connected by means of an elbow 30 to a pipe 31 leading to the atmosphere, stack, or a suitable recuperator.

32 is a combustion chamber block made of fire brick or other refractory material having an inwardly diverging circular opening or combustion chamber 33 in its center and in alignment with the radiant tube 29. The outside of this block is square shaped and is surrounded by a supporting metal shell 34 which covers the front and sides of the block 32, leaving the small end of the combustion chamber 33 exposed, and which shell is flanged at 35 at 80 its rear end to lie against and conform to the outline of the flange 27.

36 and 37 are tie rods screwed into flange 27 through corresponding holes in the flanged portion 35 of the shell 34. Nuts 38 engaging 95 the threaded ends of the tie rods furnish additional means besides the usual bolts (not shown) to hold the supporting shell 34 and with it the block 32 tightly against the flange 27.

39 and 40 are T fittings engaging, respectively, with their center connections outwardly extending theraded ends of rods 36 and 37.

5 Midway between the T fittings 39 and 40, and in central alignment with the combustion chamber 33, is an oil burner 41, having an outlet nozzle 42 and a regulating valve 43. This burner is, preferably, of the kind which may 10 use either oil or gas for fuel. Union connections 44 and 45 are interposed between the T fittings 39 and 40 and the burner to facilitate the assembling of the parts. Into the other end of T 39, opposite the one into which 15 union 44 is screwed, is connected a short pipe nipple 46 which in turn is threaded to a stop valve 47 of commercial form for the purpose of regulating the air supply admitted through a pipe 48. The other end of T 40, opposite the one into which union 45 is screwed, is also provided with a short pipe nipple 49 connected to an oil strainer 50 of standard design, another short nipple 51, and a stop valve 52 which regulates the oil admitted 20 through a pipe 53.

25 The arrangement of parts, exterior of the oven, just explained, is preferably identical with the one disclosed in Patent No. 1,574,839, issued to me on March 2, 1926.

30 In Fig. 2, the radiant tube is shown in direct alignment with the combustion chamber and the burner. In the modification illustrated in Fig. 3, however, a plurality of tubes may be connected together by a firing manifold 54 which is in alignment with the combustion chamber 33, the radiant tubes to be connected to this manifold, and their outwardly projecting ends at the rear of the oven, may be connected to a common exhaust manifold 55.

40 In the variation shown in Fig. 4 part of an oven of especially great length is shown in which a number of radiant tubes 29 are connected in series by means of fittings 56, one 45 branch of each of which is in alignment with a combustion chamber 33 at the side of the oven.

45 Figs. 5 to 10 show various types of ovens and combinations of radiant tubes to suit different kinds of work to be treated at different 50 temperatures.

55 In Fig. 11 are shown various cross sections of the radiant tube, round at 29, square at 29^a, rectangular at 29^b, and oval at 29^c. The longitudinal shape of the tube 29 may be either plain as shown in Figs. 2 to 4, or corrugated as shown in Fig. 12 at 29^d or finned as shown at 29^e in Fig. 13.

60 The operation of the device is as follows: Oil is admitted, under pressure, from supply pipe 53, through valve 52, whence it passes through nipple 51, strainer 50, nipple 49, T fitting 40, and union connection 45 into the burner 41 by way of regulating valve 43.

65 Air is admitted, also under pressure, from

70 pipe 48, controlled by valve 47, through nipple 46, T fitting 39, and union connection 44 into the burner 41. The air and oil are thoroughly mixed within the burner 41 and discharged in form of a vapor through nozzle 42 into the combustion chamber 33 where the vapor is ignited by burning waste or other suitable means. The resulting flame is then projected into the tube 29, which becomes incandescent or radiant and radiates heat from all points of its circumference into the work chamber. No products of combustion come in contact with the material being treated in the work chamber, but they are carried off at the far end of the tube either directly to the atmosphere or to a stack or recuperator. Various kinds and forms of heat resisting metal may be used for the tubes, and any suitable sectional shape for the tubes may be employed. By regulating the flame, a greater or lesser degree of radiant heat may be obtained with the same ease with which electrical heating elements are regulated.

75 Attention is particularly drawn to the fact that transmission of heat is effected entirely by radiation, no flame coming in direct contact with the work, nor is the heat concentrated upon any point. Besides by regulation of the flame, the heat may be controlled by choice of materials of the tube walls. This enables 80 the use of the highest combustion temperature to obtain the best fuel economy without damage to the product by overheating.

85 It is also pointed out that the initial cost of 90 an oven made according to the principles of my invention is a very low one, and that it is very economical to maintain, owing to the simplicity of its construction and the cheap fuel used. Its working characteristics are 95 practically identical with expensive electrically operated ovens in which electrical elements radiate heat, but its cost of operation is but a fraction thereof.

100 The particular construction disclosed lends 105 itself especially to ready replacement of heating elements or tubes. If gas be substituted for oil, the manner of operation will be the same as the one described above for oil.

110 It is understood that various changes in the 115 form, proportion and minor details of construction may be resorted to, without departing from the principles or sacrificing any of the advantages of the invention, as defined in the appended claims.

115 What I claim as new, is:

120 1. In an oven, a heating element comprising a tube adapted to radiate heat, having means externally of the oven to propagate a flame into the tube at its one end, its other end providing an outlet for the products of combustion, and additional means externally of the oven intermediate between the said ends of the tube to propagate flames into the said tube.

125 2. A heating element for an oven comprising an oil burner, a combustion chamber, a

tube projecting through the oven adapted to become incandescent for the purpose of radiating heat, and a flange removably secured to the outside of the said oven supporting the said tube, chamber and burner, the said tube having one outlet for products of combustion externally of the said oven.

In testimony whereof I have hereunto set my hand.

ALBERT W. MORSE.
